ILLUMINATED SIGN

William P. Shine, Monroe, Conn., assignor to Dual-Lite
Company, Newtown, Conn.

Filed Mar. 11, 1974, Ser. No. 449,736

Term of patent 14 years

Int. Cl. D20—03

U.S. Cl. D96—12 R

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 13

FIG. 14

FIG. 1 is a front perspective view of an illuminated sign showing my new design;

FIG. 2 is a front elevation view of the illuminated sign of FIG. 1;

FIG. 3 is a rear elevation view of the illuminated sign of FIG. 1;

FIG. 4 is a top plan view of the illuminated sign of FIG. 1;

FIG. 5 is a bottom plan view of the illuminated sign of FIG. 1;

FIG. 6 is an enlarged end elevation view of the illuminated sign of FIG. 1, the opposite end elevation view being identical thereto;

FIG. 7 is a diagrammatic cross-sectional enlarged end elevation view showing the front and rear faces of the illuminated sign of FIG. 1;

FIG. 8 is a front perspective view of a similar illuminated sign comprising a second embodiment of the invention;

FIG. 9 is a front elevation view of the illuminated sign of FIG. 8;

FIG. 10 is a rear elevation view of the illuminated sign of FIG. 8;

FIG. 11 is a top plan view of the illuminated sign of FIG. 8;

FIG. 12 is a bottom plan view of the illuminated sign of FIG. 8;

FIG. 13 is an enlarged end elevation view of the illuminated sign of FIG. 8, the opposite end elevation view being identical thereto; and

FIG. 14 is a diagrammatic cross-sectional enlarged end elevation view showing the front and rear of the illuminated sign of FIG. 8.

The indicia is shown in broken lines for illustrative purposes only.

I claim:

The ornamental design for an illuminated sign, substantially as shown and described.
